CUTTER

Ernest C. Neal, Chicago, Ill., assignor of one-fourth to James D. Roberts, Portland, Oreg., and one-fourth to Francis E. Marsh, McMinnville, Oreg.

Application October 13, 1939, Serial No. 299,239

9 Claims. (Cl. 30—231)

This invention relates to a cutter or cutting element or device for cutting cables principally, but also for cutting bars, rods and the like.

The primary object of the invention is to provide a cutter which is relatively light in weight so the same may be moved readily from one location to another, which is provided with new and improved mechanism so as to provide great leverage to effect and insure relatively easy operation during cutting; which is strong and durable in construction; which is easy and efficient in operation; which is composed of relatively few and simple parts; and which is not likely to get out of order.

A further important object of the invention is the provision of a cutter which has a long pivotally mounted operating bar providing great leverage so as to rotate a cutting jaw in the form of a circular rotatively mounted ratchet operating member having peripheral ratchet teeth, the bar being operated in the cutting stroke by a cam on an operating lever whereby a compound leverage principle is provided to insure positive and easy cutting.

Still another object of the invention resides in the construction and arrangement of the parts whereby the movement of the cutter toward cutting position is prevented from moving in a reverse direction, a condition which is likely to exist because of the inherent springy characteristics of the material to be cut, such as cables or cable material.

Another object of the invention is to provide a cutter which has a compound leverage principle of operation to produce positive cutting with the application of a relatively small amount of force to operate a rotatively mounted pawl operated ratchet cutter.

Numerous other objects and advantages will be apparent throughout the progress of the following specification.

The accompanying drawing illustrates a selected embodiment of the invention and the views therein are as follows:

Fig. 1 is a detail elevational view of the improved cutter;

Fig. 2 is a detail top plan view thereof;

Fig. 3 is a detail sectional view on the line 3—3 of Fig. 1; and

Figs. 4, 5 and 6 are detail vertical sectional views on the lines 4—4, 5—5 and 6—6 of Fig. 1, respectively.

The cutter or cutting device herein shown for the purpose of illustrating the invention comprises a base or frame support 10, in the form of

a channel, having a bottom 11, front and rear sides 12 and 13, respectively, and ends 14 and 15, the end 14 being closed and the end 15 being open at or near its upper end. The sides 12 and 13 terminate in upwardly extending portions 16 to form supports or bearings for a transverse shaft or axle 17. This axle 17 has mounted thereon a circular element 18 which is preferably in the form of a wheel. The element or wheel 18 may be rotatively mounted on a non-rotatable axle 17 or the wheel 18 may be fixed to a revolvably mounted axle 17, just so rotary movement may be given thereto.

This element 18, in the form of a wheel, gear, sprocket or the like, is cut away as indicated at 19, Fig. 1, to provide a jaw 20, the material at one side of the cut-away being beveled or curved to provide a suitable movable cutting edge 21. This cutting edge or cutting jaw 21 co-operates with a fixed or stationary cutting jaw or cutting edge 22 formed on the extending or projecting edge 23 on the front side member 12 of the base support 10. The cutting jaws 21 and 22 are adapted to co-operate with each other so as to cut a cable, rod, bar, or the like therebetween.

The element 18 is mounted for rotative movement which is given thereto progressively by means of an operating ratchet pawl 24 adapted to engage ratchet teeth 25 formed on a part of the periphery. The pawl 24 is substantially the same width as the wheel 18, and it is pivotally mounted at 26 to a longitudinal bar or lever member 27 which is mounted for vertical oscillatory movement on the shaft or axle 17.

The bar or lever member 27 comprises two side bars 28 and 29 which engage the outsides of the side members 12 and 13, respectively, the side pieces 28 and 29 being connected for a part of their lengths by a top piece or plate 30. The top bar is thus guided by the side flanges 28 and 29 and is prevented from shifting laterally. The free end of the lever member or bar 27 has a roller 31 mounted thereon which is adapted to engage an operating cam member 32 on an operating member or lever arm 33. The arm 33 is pivotally mounted on a horizontal axis 34 carried by the sides 12 and 13, and it is in the form of a socket to receive a long handle 35 to provide great leverage. When the handle 35 is oscillated forwardly (to the right, Fig. 1), the cam 32 engaging the cam roller 31 will raise the free end (the end at the left, Fig. 1) of the lever bar 27, and inasmuch as the pawl 24 is carried by this lever bar 27 and in engagement with the ratchet teeth 25, the movement is transmitted to

the cutting wheel 18 causing the wheel 18 to rotate and bring the cutting jaw 21 toward the stationary cutting jaw 22. Upon movement of the handle to the left, Fig. 1, the bar 27 will return to its normal position (Fig. 1) by gravity, the pawl 24 merely riding over the teeth 25 on the return stroke.

Cable, or other material to be cut, may be of a relatively springy nature, and therefore means are provided to hold the cutting jaw 20 in place and against the cable so that the wheel 18 will be prevented from rebounding or rotating in a counterclockwise direction. This means may comprise a second ratchet pawl 36 which is so positioned that when the wheel 18 is rotated at least one tooth 25, it will fall in between a pair of teeth 25, the pawl 36 being so arranged as to hold the wheel 18 against reverse movement when the pawl 24 rides over the teeth on the return stroke. The pawl 36 is mounted on a horizontal axis 37 which is suitably supported by the sides 12 and 13 of the frame support 10. After the cable, bar, rod or other member is cut the pawl 36 should be released. Therefore, a projection or finger 38 is fixed or otherwise fastened to the pawl, there being an arcuate opening 39 formed in the side 12 to permit operation of the pawl. The arcuate slot 39 is of a length sufficient to permit the pawl to engage the teeth 25 or to be swung on its axis 37 out of engagement and supported in out of the way position. In this latter position the finger 38 will be in the extreme left hand edge of the slot 39, Fig. 1. As the material to be cut may cause a binding action of the cutting jaws, force may be necessary to free or ease the wheel 18, and therefore a socket 40 is formed in an advantageous location in the periphery of the wheel into which a bar or other lever may be inserted to return the wheel to its normal position, Fig. 1. To return the wheel 18 to its normal position the pawl 36 of course must first be released. The releasing of the pawl 36 may be accomplished by shifting the finger 38 from the right hand end of the slot 39 to the left hand end of the slot.

To make the device ambulatory, so as to permit it to be moved readily from one position to another, two or more wheels or rollers 41 are provided. These rollers 41 are mounted on suitable axles 42 mounted in lugs or ears 43 fastened to the supporting base 10. These lugs or ears may be fastened to the base in any suitable manner, or they may be formed integral therewith as shown. Also, to permit the device to be handled an end handle 44 and side handles 45 may be provided. The handle 44 is preferably similar to a wagon tongue while the side handles may be in the form of rigid loops fastened to the sides 12 and 13 in any suitable manner, such as by welding.

The invention provides a rigid, durable cutter of simple design for cutting bars, rods and principally cable. The device can be moved readily and easily from one position to another and because of its simplicity can be economically manufactured. Because of the compound lever action herein provided, very great leverage can be obtained, the leverage being multiplied because of the particular association of the two levers which operate the driving ratchet pawl. Moreover, the device consists of few and simple parts, and while designed principally for cutting cables, it can be used successfully for cutting bars, rods and other articles of material.

Changes may be made in the form, construc-

tion and arrangement of the parts without departing from the spirit of the invention or sacrificing any of its advantages, and the right is hereby reserved to make all such changes as fairly fall within the scope of the following claims.

The invention is hereby claimed as follows:

1. A cutter comprising a base, a cutting jaw on one side of the base, a co-operating pivotally mounted member having a cutting jaw adapted for co-operation with the first cutting jaw, a ratchet pawl for moving the member in one direction, a lever arm pivotally mounted adjacent the pivotal axis of said co-operating member for operating the pawl, and a second separately mounted lever arm for operating the first named lever arm.

2. A cutter comprising a stationary cutting jaw and a movable cutting jaw, an operating ratchet pawl for moving the movable cutter about an axis, a lever arm pivotally mounted on said axis for operating the pawl, and a second pivotally mounted lever arm cooperating with said first lever arm at a position spaced from said axis for operating the first named lever arm.

3. A cutter comprising a stationary cutting jaw, a rotatively mounted member having a cutting jaw adapted for cutting in co-operation with the first jaw, ratchet teeth on the rotatively mounted member, a ratchet pawl co-operating with the teeth to impart rotative movement to the member, a lever arm movable about the axis of said rotatively mounted member carrying the pawl and causing operation thereof when operated, and a second lever arm co-operating with said first lever arm at a position spaced from said axis for operating the first lever arm.

4. A cutter comprising a stationary cutting jaw, a rotatively mounted member having a cutting jaw adapted for cutting in co-operation with the first jaw, ratchet teeth on the rotatively mounted member, a ratchet pawl co-operating with the teeth to impart rotative movement to the member, an elongated lever arm carrying the pawl and causing operation thereof when operated, a roller on the lever arm, and a separately mounted cam member co-operating with the roller to operate said lever arm.

5. A cutter comprising a stationary cutting jaw, a rotatively mounted member having a cutting jaw adapted for cutting in co-operation with the first jaw, ratchet teeth on the rotatively mounted member, a ratchet pawl co-operating with the teeth to impart rotative movement to the member, a pivoted lever arm carrying the pawl and causing operation thereof when operated, a second pivoted lever arm separately mounted on an axis spaced from the pivotal axis of said first lever arm and having means thereon for operating the first lever arm, and a second pawl co-operating with teeth to hold the member in position when moved by the first pawl.

6. A cutter for cutting cables, rods, bars and the like comprising a frame including elongated sides, at least one of said sides having a cutting jaw, a rotatively mounted wheel-like member arranged between said sides and having a cutting jaw adapted for co-operation with the first cutting jaw, an elongated lever arm having guide flanges thereon engaging at least one of said elongated sides, a ratchet means carried by the elongated lever arm and operated thereby to rotate the said member to move the second named jaw toward cutting position with respect to the first named jaw, a cam wheel carried by the lever arm; a separately mounted pivotal cam co-op-

erating with the wheel to operate the lever arm, and a lever for operating the cam.

7. A cutter for cutting cables, rods, bars and the like comprising a frame including sides, at least one of said sides having a cutting jaw, a rotatively mounted wheel-like member arranged between said sides and having a cutting jaw adapted for co-operation with the first cutting jaw, a lever arm having guide flanges thereon engaging at least one of said sides, a ratchet carried by the lever arm and operated thereby to rotate the said member to move the second named jaw toward cutting position with respect to the first named jaw, a cam wheel carried by the lever arm, a pivotally mounted cam co-operating with the wheel to operate the lever arm, a lever for operating the cam, a pawl to hold the said member in moved position when moved by the ratchet and preventing reverse movement of the member, wheels on the frame, and handles fastened to the frame.

8. A cable cutter comprising a frame, a pivot pin carried by the frame at one end thereof, a cutter element mounted on the pin, a lever arm

5 pivotally mounted on said pin, a ratchet pawl carried by the lever arm to operate the cutter element, co-operating cutter jaws on the cutter element and frame, a cam member adapted for reciprocation pivoted to the frame at the end opposite to the cutter element, a member on the lever arm and co-operating with the cam to cause operation of the lever arm by the cam, and a handle lever for operating the cam.

10 15 20 9. A cable cutter comprising a channel frame, a lever in the form of an inverted channel pivotally mounted to the frame and having interfitting engagement with the channel frame whereby the lever is guided by the frame, a cutter pivotally supported in the frame between the frame channel legs, co-operating cutting jaws on the frame and cutter, a wheel carried by the lever arm, a reciprocating cam pivotally mounted in the frame between the frame channel legs and adapted to raise and lower the lever, a handle for operating the cam, and a ratchet pawl carried by the lever and adapted to operate the cutter upon operation of the lever arm by the cam.
